UNITED STATES PATENT OFFICE.

REGINALD W. BUSSE, OF SHEBOYGAN, WISCONSIN.

CUSHION-STUFFING MACHINE.

Application filed June 16, 1924. Serial No. 720,348.

To all whom it may concern:

Be it known that I, REGINALD W. BUSSE, a citizen of the United States, and resident of Sheboygan, in the county of Sheboygan and State of Wisconsin, have invented certain new and useful Improvements in 5 Cushion-Stuffing Machines; and I do hereby declare that the following is a full, clear, and exact description thereof.

10 This invention relates to cushion stuffing machines.

In cushion stuffing machines as heretofore constructed, it has been found necessary to provide a relatively frail box construction 15 for receiving the springs and filling, and it has been necessary in these prior structures to provide an extensive space for these machines.

20 Further than this, the box for receiving the filling has been movable and consequently an elaborate and non-rigid structure has resulted.

25 This invention is designed to overcome the above noted defects, and objects of such invention are to provide a cushion stuffing machine in which a stationary filling box is employed, and in which this filling box is of relatively heavy and rugged construction and is extremely rigid.

30 Further objects are to provide a cushion stuffing machine which requires a small amount of floor space, which is relatively compact, which is positive in operation, and which is extremely rapid without requiring 35 great attention of the operator.

Further objects are to provide a cushion stuffing machine in which only one motion of the operator is required to insert the cushion filling material, and in which the 40 plunger for inserting this filling material is automatically retracted after the filling operation and the machine is automatically stopped.

An embodiment of the invention is shown 45 in the accompanying drawings, in which:—

Figure 1 is a longitudinal sectional elevation of the machine showing the plunger in retracted position.

Figure 2 is a corresponding view showing 50 the plunger in partly extended position.

Figure 3 is a front elevation of the machine showing the filling receiving box in its open position.

Figure 4 is a vertical sectional view on 55 the line 4—4 of Figure 1.

Figure 5 is a detail of one of the guides.

The machine comprises a pedestal like hollow supporting frame 1 within which the major portion of the mechanism is housed. This frame carries at its upper end the bed plate 2 which is preferably provided with downwardly extending flanges 3 fitting over the support 1 and forming therewith an extremely rigid structure. The bed plate 2 provides a slide way for the plunger rack 4, such rack being guided by forward guide members 5 and rear guide members 6. The rear guide member and if desired the forward ones may be spring pressed into position, as indicated in Figure 5, and may comprise an overhanging portion provided with a guiding flange 7. When the spring pressed guide is employed, it may be conveniently formed with a pivot contact portion 8 engaging the upper face of the bed plate and with an aperture through which an attaching bolt 9 passes, a helical spring 10 loosely surrounding the bolt and bearing downwardly upon the guide. The forward end of the rack 4 rigidly carries a rectangular 80 plunger 11, as may be seen from Figures 1, 2 and 3.

The filling receiving box is supported by means of a transverse member 12 bolted to an adjustable front plate 13. This front plate 13 is provided with an elongated slot 14 through which a clamping bolt 15 passes. If desired, this front plate 13 may be adjusted by means of a screw 16 or similar member threaded through the lower flange 90 17 of a plate 18 bolted to the front of the pedestal support 1. The transverse support 12 for the box is provided with upstanding marginal portions 19 which carry a rigid 95 guide rod 20. These upstanding ears or lugs 19 also carry a reversely threaded screw 21, such screw being held in place by a suitable collar or other equivalent device and being provided with a manipulating hand wheel 22.

The stuffing receiving box comprises a pair of bottom members 23 and 24 arranged in overlapping relation, as may be most clearly seen from Figure 3. These bottom members are provided with nuts 25 and 26 which are threaded upon the reversely threaded portion of the screw 21 so that they will simultaneously approach or recede from each other upon rotation of the hand wheel 22. If desired, a centrally located supporting member 27 may be positioned below the overlapping portions 23 and 24 of the bottom, and may thus support in a rigid 100 105 110

manner, such overlapping portions. The members 23 and 24 are provided with upwardly extending ends 28 and 29 which pivotally carry the top flaps 30 and 31, respectively. This box is adapted to be opened up, as shown in Figure 3, and to receive the springs encased in padding or similar material. When the box has received its charge, the flaps 30 and 31 of the top are rocked downwardly into overlapping position. In order to prevent these top members from moving upwardly when the filling is compacted, a relatively heavy bar 32 is adapted to be swung downwardly, as shown in Figure 1, and to reinforce the overlapping portions of the flaps 30 and 31 of the top. A convenient way of arranging this upper reinforcing strap or bar is to pivot it between lugs of a bracket 33 supported from the bed plate. A latch 34 is pivotally carried by the bar 32, and is spring pressed towards its inner position, as illustrated in Figure 1. This latch is adapted to hook beneath a portion of the bracket 33, as shown in Figure 1, to retain the bar 32 in its operative position.

It will be seen that when the operator desires to manipulate the bar 32, he may do so through the medium of the latch handle 35, thus unlatching the bar and rocking it to inoperative position.

When the filling has been placed within the box, the flaps 30 and 31 of the box are rocked downwardly and, thereafter, the bar 32 is rocked into operative position, as shown in Figure 1. The hand wheel 22 is then rotated to force the sides or ends 28 or 29 towards each other the desired extent and to thus compact the filling as required. Thereafter, the open ended cover 36, as shown in dotted lines in Figure 1, may be slipped over the outwardly extending filled box, and the mechanism manipulated to project the plunger 11 outwardly thus ejecting the filling and forcing it into the cover 36 in a uniform, even and firm manner.

The mechanism for operating the plunger is such that the operator is called upon merely to initiate the outward motion of the plunger. The mechanism automatically retracts the plunger and, thereafter, stops the machine ready for another cycle of operation.

This mechanism may comprise a pair of intermeshing pinions 37 and 38 carried by the outer arms of a triangular rock member 39, such member being provided with adjustable stops 39' and with a downwardly extending lug 40 to which a separate arm 41 is rigidly attached. These pinions are adapted to selectively engage the rack 4 and as they rotate in opposed directions, to impart reverse reciprocatory motion to the rack 4,--the pinion 38 serving to project the plunger, and the pinion 37 serving to re-

tract the plunger. The lower end of the arm 41 is connected by means of a link 42 with an upwardly extending arm 43 of a foot pedal 44 although, obviously, a hand operated device might replace the foot pedal. The lower end of the control arm 41 is further connected by means of a link 45 with the lower end of a lever 46, such lever being pivoted intermediate its ends, as indicated at 47. The upper end of the lever 46 passes through a slot 48 in the bed plate 2 and is arranged in proximity to one side of the rack 4. The rack 4 is provided with a forwardly located pin 49 and with a rearwardly located pin 50, as may be seen from Figures 1 and 2. These pins are adapted to engage the upper end of the lever 46 at the extreme portions of the stroke of the rack 4 and to thus rock the lever and shift the oscillatory member 39, thus controlling the operation of the plunger. A quick motion device is employed for aiding in rocking the oscillatory member 39 into plunger retracting position. This mechanism may comprise a tubular member 51 pivoted to the lug 40 of the oscillatory member. This tubular member 51 slidably receives a rod 52, the lower end of such rod being pivotally carried by the pin 53 of a bracket 54. This bracket is adjustably carried by a stationary portion 55 of the machine, such stationary portion being provided with an elongated slot through which a clamping bolt 56 extends, as shown in Figure 2. Thus by adjusting the position of the bracket 54, the action of the quick motion mechanism may be initially controlled. Lock nuts 57 are threaded upon the lower end of the rod 52 and adjustably compress a helical spring 58 loosely surrounding such rod, the upper end of the spring bearing against the lower end of the tubular member 51.

Any suitable form of drive may be employed for rotating the pinions 37 and 38. A convenient way of rotating these pinions is to provide a relatively small pinion 59 rigid with a sprocket wheel 60, such pinion being intermeshed with the pinion 38. This sprocket wheel 60 is connected by means of a chain 61 with a sprocket wheel 62 carried by a shaft 63. This shaft may project outwardly beyond the support 1, and may be provided with an outer pulley 64, although, obviously, a motor may be employed in place of the driving pulley 64.

The operation of the apparatus is as follows:—The box is thrown into open position, as shown in Figure 3, and the filling, such as box springs surrounded loosely by batting is placed within the box. Thereafter, the covers 30 and 31 are swung downwardly and bar 32 is swung into locked position. The exact width for the box is attained by adjusting the hand wheel 22, as previously described. The operator then in-

serts the open ended casing 36 for the cushion over the filled box. Thereafter, he 5 presses the pedal 44, thus rocking the oscillatory member 39 in a clockwise direction and causing the pinion 38 thereof to engage the rack 4. This projects the plunger 11 forwardly and ejects the filling material in an even and uniform manner positively 10 positioning it within the casing 36. As the plunger rack 4 travels forwardly, the rearmost pin 50 engages the upper end of the lever 46 and rocks the oscillatory member 39 in a counter clockwise direction, such motion being aided by the quick motion mechanism 15 described. This places the retracting pinion 37 in engagement with the plunger rack 4 and the plunger is thus automatically retracted. When the plunger arrives at its rearmost position, the pin 49 rocks the lever 20 46 and through the link mechanism rocks the oscillatory member 39 in a counterclockwise direction. However, the set of the quick motion mechanism is such that the oscillatory member is merely rocked into the 25 position shown in Figure 1 without being moved completely over into the plunger advancing position. The rack is held by the spring pressed guide 6 against inadvertent reciprocation and the machine thus automatically 30 stops at the completion of this cycle of operation.

It will thus be seen that a cushion stuffing machine has been provided in which a rigidly mounted filling receiving box is provided, and in which simple and rapid means are employed for adjusting the box to its desired position, it being understood that the screw 21 is of relatively high pitch.

It will be seen that a very simple and positive power stuffing mechanism is provided whose operation is initiated by a single motion of the attendant.

It is to be noted further that the plunger is automatically retracted after the stuffing 45 operation and the machine is automatically

stopped when the plunger is completely retracted.

Although the machine has been described specifically as a cushion stuffing machine, it is, of course, understood that any type of similar articles may be stuffed upon this machine, and that, therefore, the term "cushion stuffing" appearing in the specification and claims is not to be interpreted in a limiting sense.

Although the invention has been described in considerable detail, it is to be understood that the invention may be variously embodied and is, therefore, to be limited only as claimed.

I claim:

1. A cushion stuffing machine comprising a filling receiving box, a plunger mounted therein, a rack bar attached to said plunger, a pair of reversely rotating pinions adapted to selectively engage said rack bar, manual means for causing one of said pinions to engage said rack bar to advance said plunger, and automatic means for causing the other of said pinions to engage said rack bar for retracting said plunger.

2. A cushion stuffing machine comprising a filling receiving box, a reciprocating plunger positioned therein and having a rearwardly extending rack bar, an auxiliary member having a pair of reversely rotating pinions thereon, manually controlled means for rocking said auxiliary member in one direction to cause one of said pinions to engage said rack bar and lever mechanism operated from said rack bar for automatically rocking said auxiliary member in the other direction to cause the other of said pinions to engage said rack bar.

In testimony that I claim the foregoing I have hereunto set my hand at Sheboygan, in the county of Sheboygan and State of Wisconsin.

REGINALD W. BUSSE.
